LAMP

Richard M. Hanellin, Far Rockway, and Beatrice H.
Baldwin, Merrick, N. Y.

Application April 20, 1954, Serial No. 30,097

Term of patent 14 years

(Cl. D48—20)

We claim:
The ornamental design for a lamp, as shown.
